UNITED STATES PATENT OFFICE.

JULIAN L. PERKINS, OF WEST SPRINGFIELD, AND JOHN OAKLEY, ROBERT A. WILSON,
AND HIRAM D. CROFT, OF SPRINGFIELD, MASSACHUSETTS, ASSIGNEES TO PERKINS
APPLIANCE COMPANY, OF SPRINGFIELD, MASSACHUSETTS, A CORPORATION OF
MASSACHUSETTS.

WORKTABLE.

Original application filed February 13, 1922, Serial No. 536,160, Patent No. 1,486,604. Divided and this application filed July 9, 1923. Serial No. 650,405.

Our invention relates to improvements in work tables, and consists generally of a pair or plurality of work holders mounted on a turn-table whereby said work holders can be located alternately in and out of operative position, the same having an orbital path around a common center, means and mechanism for securing the work on and to said holders, removable supporting means for the top of the work holder which is in operative position, and locking and releasing, and operating means for said turn-table, together with such other parts and members as may be necessary or desirable in order to render the work table complete and serviceable in every respect, all as hereinafter set forth.

5 for the top of the work holder which is in operative position, and locking and releasing, and operating means for said turn-table, together with such other parts and members as may be necessary or desirable in order to 10 render the work table complete and serviceable in every respect, all as hereinafter set forth.

15

This work table is especially adapted for a vertical broaching machine, such as that 20 which forms the subject of our application for Letters Patent No. 1,486,604 of the United States, filed February 13, 1922, Serial No. 536,160, of which application the 25 present application is a divisional part, although said work table is not limited to machines of that type.

One object of our invention is to produce a work table which is capable of having mounted thereon and secured thereto stacks 30 of blanks for ring gears or the like, and for supporting and carrying such blanks while the same are being cut.

A further object is to provide a work table of this character wherewith one set of 35 blanks can be placed in position and made ready for cutting or broaching while another set of blanks is being cut or broached, the loading and unloading operations being performed by the operator.

40 Another object is to provide for such work table means whereby the same can be conveniently, practically, and efficiently controlled and operated by the hand and foot.

Still another object is to furnish locking 45 devices for the movable parts of or associated with the work table, to the end that improper movements at improper times are prevented, and said table is rendered safe and reliable as well as highly efficient.

50 Other objects and advantages will appear in the course of the following description.

A preferred embodiment of the invention,

whereby we attain the objects and secure the advantages of the same, is illustrated in the accompanying drawings, and we will 55 proceed to describe the invention with reference to said drawings, although it is to be understood that the form, construction, arrangement, etc., of the parts in various aspects are not material, and may be modified without departure from the spirit of 60 the invention.

In the drawings, in which similar reference characters designate similar parts throughout the several views, Figure 1 is a 65 top plan of a work table which embodies our invention as aforesaid, showing the same applied to a broaching machine; Fig. 2, an enlarged, top plan of the bearing disk carried by the yoke; Fig. 3, an enlarged, horizontal section through said machine and work table, taken on lines 3—3, in Fig. 6; Fig. 4, a side or what may be termed front elevation of said machine and work table, 70 with portions of the frame broken out to disclose interior elements; Fig. 5, an end elevation of said machine and work table; Fig. 6, an enlarged, vertical section through the machine and work table, with top and bottom portions omitted, such section being 75 approximately in the vertical, longitudinal center or work plane of the machine; Fig. 7, an enlarged, top plan of the manually-operated and pedally-operated lever mechanism of the work table; Fig. 8, an enlarged, 80 bottom plan of a portion of the base of the frame of the machine, showing the pivots and their bearing lugs for certain of the elements in the aforesaid mechanism, together with the rock-shaft lock member of 85 such mechanism; Fig. 9, a back side elevation of said mechanism as shown in Fig. 7, and, Fig. 10, an enlarged detail of said lock member. 90

The cutting or work plane hereinbefore 95 referred to is on lines α — α in Fig. 1.

The machine illustrated in the aforesaid application is a double or duplex machine throughout, and the mechanism on either side of the transverse center of said machine 100 forms a complete unit. In the present case we have shown one of such units, the same being the right-hand unit.

It will be desirable, not to say necessary,

to describe briefly the broaching machine to which our work table is applied in the present example, before describing the work table itself.

5 The frame of the machine comprises a base 1, and two uprights 2 mounted on said base and connected at the top by a member 4. The uprights 2 extend below the floor line into a receptacle 5 for waste oil and 10 chips, the frame also comprises bearing and other parts of which particular mention will be made as or when necessary.

15 For the sake of convenience in describing the machine and work table, the side illustrated in Fig. 4 will be considered as the front and the opposite side as the rear.

20 The machine is provided with a vertical broach carrier 6 arranged to slide up and down and contact with the outer edges of the uprights 2. On the inside of the carrier 6 in the transverse center thereof is a rack 7 with which a gear 8 intermeshes. The gear 8 is driven by a gear 9. Journaled in the uprights 2 and in suitable bearings 25 with which said uprights are provided, one above the other in the order named, are horizontal shafts 10, 11, and 12. Secured on the forward terminal of the shaft 10 is a main driving gear 13. Secured on the 30 rear terminal of the shaft 10 is a pinion 14, and such pinion intermeshes with a gear 15 secured on the rear terminal of the shaft 11. The gears 9 and 8 are respectively secured to the shafts 11 and 12. Thus means are 35 provided for reciprocating the rack 7 and the carrier 6.

40 A broach holder 16 is mounted to oscillate on its vertical axis in the carrier 6. Secured within the holder 16 in different radial planes thereof are pluralities of 45 roughing and finishing broaches 17 and 18, respectively. The broaches 17 cut on their down stroke and the broaches 18 cut on their up stroke. Operatively either the roughing broaches or the finishing broaches are in the work plane $x-x$, the holder 16 being oscillated between strokes.

50 Journaled in the uprights 2 and projecting beyond the front side of the front upright are two horizontal rock-shafts 19-19. The rock-shafts 19 are provided on their front terminals, which terminals extend beyond the front upright 2, with arms 20 and 21. The arm 20 extends downwardly to the left from the upper rock-shaft 19, and the arm 21 extends downwardly to the right from the lower rock-shaft 19. A connecting-rod 22 has each end pivotally attached at 23 to the arms 20 and 21, the upper terminal of 55 said rod being connected with the free terminal of said first-named arm, and the lower terminal of said arm being connected with said second-named arm intermediate of its ends. The construction and arrangement of the parts are such that, if the con-

necting-rod 22 be raised, the arms 20 and 21 are swung upwardly in a manner to carry the pivots 23 through corresponding arcs, said arms rocking on and with the rock-shafts 19. These parts and members together form a portion of the mechanism by means of which the broach carrier 16 is oscillated, and with which the present application is not concerned, but they also together constitute a portion of the work-table mechanism, as will subsequently be made clear.

60 The connecting-rod 22 is raised and lowered by means of a manually-operated lever 24 which is pivotally connected at 25 with an oblique web 26 that extends forwardly and to the right from the front upright 2. The pivot 25 is set in the web 26. The web 26 is provided with a sector 27 in which there are two radial openings 28, as shown in Fig. 9. The inner terminal of 65 the lever 24 is forked as shown at 29, and such terminal embraces the connecting-rod 22 between two flanges 30 thereon. Said lever is provided with a latch-rod 31, adapted at its inner terminal to enter either of the 70 openings 28 in the sector 27. A keeper 32 is provided on the lever 24, adjacent to the sector 27, to serve as a guide for the latch-rod 31. At the outer end of the lever 24 is a handle 33. The outer end of the latch-rod 31 is connected with a latch 34 which is 75 pivotally connected at 35 with the lever 24, adjacent to the handle 33. The latch 34 is extended outwardly alongside of the handle 33, and a spring 36 is interposed between 80 the extended part of the latch and said handle, so that said part is normally held away from said handle, and the latch-rod 31 permitted to enter into and remain in 85 locking engagement with the sector 27. 105

90 When the inner end of the latch-rod 31 is in the upper opening 28, the connecting-rod 22 is thereby locked in its low position. Before the connecting-rod 22 can be raised, it is necessary to grasp the handle 33 with 95 the extended part of the latch 34, and force such part, against the resiliency of the spring 36, toward said handle, whereby said latch is rocked on the pivot 35 and the latch-rod 31 drawn out of the upper opening 28. 110 The lever 24 can now be rocked on its pivot 25 to raise the terminal 29 thereof and with it the connecting-rod 22. After thus elevating the connecting-rod 22, the latch 34 is 115 released to its spring 36, and the latter acts to return said latch to normal position and actuate the latch-rod 31 into the lower opening 28. The lever 24 is now locked in its new position, and with it the connecting-rod 22 in elevated position. Upon again grasping the handle 33 and withdrawing the latch-rod 31 from the lower opening 28, and 120 rocking the lever 24 downwardly at the forked end, the connecting-rod 22 is lowered. The latch-rod 31 is then permit- 125 130

ted to enter the upper opening 28 when the parts and members are again locked.

A bell-crank lever 37 is pivotally connected at 38 to the back side of an intermediate wall of the base 1 below the horizontal plane of said base, Figs. 4, 7 and 9. A connecting-rod 39 has its upper terminal pivotally attached at 40 to the free end of the arm 21, and its lower terminal pivotally attached at 40 to the inner terminal of the bell-crank-lever 37. The bell-crank-lever 37 is arranged with its angle uppermost, and the angular portion of the same is the part mounted on the pivot 38. There is a horizontal bearing 41 for the pivot 38, which bearing extends from the aforesaid intermediate wall of the base, such wall being indicated by the numeral 42. A transverse rock-shaft 43 is journaled in bearings 44 and 45 in the end portion of the base 1, as shown in Fig. 8. Secured to the outer terminal of the rock-shaft 43 is an upstanding arm 46, and a connecting-rod 47 extends between said arm and the short arm of the bell-crank-lever 37, such bell-crank-lever being arranged with its short arm extending toward the adjacent end of the base 1 and its long arm extending toward the central, transverse, vertical plane of said base. The connecting-rod 47 is approximately horizontal and has its ends pivoted at 48—48 to the arm 46 and the short arm of the bell-crank-lever 37, respectively. The rock-shaft 43 has an offset 49 therein, the transverse center of which is in the work plane $x-x$ of the machine.

The rock-shaft 43 and its connections are so arranged that, when the connecting-rod 22 is in its depressed and normal position, the connecting-rod 39 is also in its depressed position, and the offset 49 is disposed vertically. Upon elevating the connecting-rod 22 and, through the medium of the arm 21, the connecting-rod 39, the bell-crank-lever 37 is actuated to draw inwardly the connecting-rod 47, and thus partially to rotate the rock-shaft 43 in the direction to carry the offset 49 from the vertical into an approximately horizontal position. A reversal of the movement of the connecting-rod 22 brings about a reverse movement of the intervening parts and members between said rod and the rock-shaft 43, and actuates the latter in such a manner as to return the offset 49 to vertical position. The offset 49 serves as a lock for a pin 50 that will presently be described.

Associated with the connecting-rod 47 and the rock-shaft 43, although not directly connected therewith, are an approximately horizontal treadle 51, and two approximately horizontal levers 52 and 53. The treadle 51 is pivotally connected at 54, intermediate of its ends, with a pair of lugs 55 with which the end portion of the base 1 is provided on

the inside; the lever 52 is pivotally connected at 56, intermediate of its ends, with a pair of lugs 57 with which said end portion is also provided on the inside; and the lever 53 has its inner end pivotally connected at 58 with a pair of lugs 59 with which said end portion is further provided. The treadle 51 extends outwardly through a slot in the end of the base, and is provided at its outer terminal with a foot-piece 60. The outer end of the lever 52 has an universal- or ball-joint connection 61 with the inner end of the treadle 51, and a similar connection 62 is provided between the outer end of the lever 53 and said treadle adjacent to the pivot 54 and between said pivot and said first-named connection. The inner terminal of the lever 52 is forked, as shown at 63. The lever 53 is provided on top adjacent to the pivot 58 with a disk or plate 64 which constitutes what may be termed a stirrup.

The treadle mechanism and the rock-shaft 43 with its offset 49 are associated with work-holding mechanism mounted on the base 1 above said first-named mechanism and said rock-shaft.

There are two supporting and carrying elements for the work, and provision is made for transposing the same so that either can be located in operative relation to the adjacent broach holder 16. We will now describe the aforesaid elements.

A normally-stationary turn-table 65 is mounted on the base 1. The turn-table has a central, vertical shaft 66 which is journaled directly above the stirrup 64, in a bearing 67 in the base 1, a ball-bearing 68 being interposed between said stirrup and the bottom of said shaft. The portion of the shaft 66 that is in the bearing 67 is larger than the portion of said shaft upon which the turn-table 65 is directly mounted, so that a shoulder 69 is formed on said shaft. Normally the turn-table rests directly on top of the base 1, and the shoulder 69 is then in the same plane with said top. The axis of the shaft 66 is in the work plane of the machine. The turn-table may or may not be rigidly attached to the shaft 66, just as is preferred.

Rising from the turn-table 65, on opposite sides of the shaft 66, are two vertical shafts 70. Each shaft 70 has a screw-threaded base with which a nut 71 is connected to anchor said base in the turn-table. Within the aforesaid base of each of the shafts 70 in the axial center thereof is an opening 72. The opening 72 in either shaft is adapted to receive the upper terminal of the lock pin 50. When either shaft 70 is engaged by the pin 50, such shaft and its companion are located with their axes in the work plane $x-x$. The pin 50 is in position to engage the inner shaft 70, the same being the shaft upon which the holder for

the work actually being operated on is mounted, or is a part of such holder.

The pin 50 is slidingly arranged in a hollow member 73 that depends from the top 5 of the base 1 in the work plane $\alpha-\alpha$, and to the left of the bearing 67 or between such bearing and the transverse, central, vertical plane of the machine. The pin 50 is provided with a stem 74 that extends 10 downwardly from the bottom of said pin and through the bottom of the member 73, there being a head 75 on the lower end of said stem. A spring 76 is interposed between the bottom of the pin 50 and the 15 bottom of the main passage in the member 73, and normally actuates said pin upwardly and retains it in engagement with the shaft 70 above. The rock-shaft 43 is so located that, when its offset 49 is vertically 20 disposed, the same is directly beneath the head 75 of the stem 74, so that said stem and the pin 50 can not be forced downwardly. The fork 63 of the lever 52 engages the stem 74 above the head 75.

25 In order to rotate the turn-table 65 about its axis, for the purpose of changing the relative positions of the work-holders of which the shafts 70 constitute parts, or, in other words, to interchange the positions of 30 said shafts, it is first necessary to unlock said turn-table by withdrawing the pin 50 from the opening 72 in the left-hand shaft 70, and then raise said turn-table with the work holders on the shoulder 59 from the 35 base 1. These results are accomplished by grasping the handle of the lever 24 and actuating said lever to withdraw the offset 49 from beneath the head 75, and placing the foot on the part 60 of the treadle 51 and actuating said treadle to rock upwardly the 40 connected terminals of the levers 52 and 53. Since the connection 61 is farther from the pivot 54 than is the connection 62, and the fulcrum of the lever 52 is nearer said connection 61 than is the fulcrum of the lever 53, the forked terminals 63 of said lever 52 moves more quickly and through a greater 45 space than does the stirrup 54 which is on the lever 53 quite near to the inner fulcrum terminal of the same, when the portion of said treadle with which said levers are connected is elevated. Consequently the 50 first effect of the depression of the outer terminal of the treadle 51 is to rock the lever 52 in such a manner as to carry the fork 63 thereof downwardly and so withdraw the pin 50 from engagement with the 55 shaft 70 above, through the medium of the head 75 and the stem 74, and against the 60 resiliency of the spring 76, which action is possible because the offset 49 is now out of the way of said head. And the second effect of the motion imparted to the treadle 65 is to raise the lever 63 and the stirrup 64. 65 The upward movement of the stirrup 64 is

transmitted through the ball-bearing 68 to the shaft 66, and the latter is elevated and carries up with it the turn-table 65 and all of the parts and members supported thereby. The upward movement of the shaft 66 70 is comparatively slight, being only sufficient to raise the turn-table 65 clear of the top of the base 1. With the turn-table thus elevated the same can be rotated on and with the shaft 66 on the ball-bearing 68. 75

After the turn-table 65 has been given by hand a half revolution, the treadle 51 is released, and said turn-table settles down again by gravity onto the base 1, and the spring 76 forces the pin 50 upwardly into the opening 72 in the base of the newly-presented shaft 70. The lever 24 is then operated to restore the offset 49 to its upright position beneath the head 75. 80

Each shaft 70 is the axis of the work 85 holder mounted on such shaft, and such holder comprises, besides said shaft, a horizontal base 77, a horizontal plate or disk 78, for a vertical cam sleeve 79, six segmental, vertical spacers or separators 80, the 90 same number of vertical friction bars 81, a horizontal head 82, and six, long, vertical rods 83 and nuts 84 therefor, together with certain other parts and members yet to be described, as illustrated more particularly 95 in Fig. 6. A ball-bearing 85 is interposed between the turn-table 65 and the base 77, so that the latter may revolve freely on the former. The cam sleeve 79 has a worm-wheel 86 secured to the base thereof, and said sleeve is shouldered at 87 to receive beneath the shoulder the edge of the opening in the plate 78 provided for the passage of that portion of the sleeve which is between said shoulder and the worm-wheel 86. 100 The worm-wheel 86 is received and operates in a central opening 88 in the top of the base 77. Also in said opening is a worm 89 which intermeshes with the worm-wheel 86. The plate 87 rests on the base 77 above the worm-wheel 86, and the separators 81 rest at their lower ends on said plate. The head 82 is on top of the cam sleeve 79 and the separators 81. Each separator has two radial arms 90, and one of the rods 83 is located between such arms, and there are top and bottom, horizontal flanges or webs 92 and an intermediate, horizontal flange or web 93 which extend between and connect said arms, and through which said rod 110 passes. The rods also pass through a flanged portion of the cap 82 and the plate 78 to be tapped into the base 77. The friction bars 81 are slidingly arranged, between the arms 90 of adjacent separators 80, on the plate 78 and under the head 82. The work, consisting in this case of a plurality or multiplicity of ring-gear blanks 94, is passed over the head 82 and down around the arms 90 and bars 81, with the bottom 115

most blank resting on a supporting ring 95 that is secured to the periphery of the disk 78. The blanks 94, after being piled or stacked one on top of the other around 5 the arms 90 and bars 81, are aligned and formed into a hollow cylinder which is concentric with the work holder, and frictionally secured by means of the cam sleeve 79, after which clamps 96, there being as many 10 of such clamps as there are rods 83, are placed in position for the further security of the stack of blanks.

The worm 89 is mounted on a shaft 97 that is journaled at both terminals in the 15 base 77, and has at one end a squared head 98, Figs. 4 and 5, to receive a wrench (not shown). Upon revolving the worm 89, through the medium of the shaft 97, the worm-wheel 86 is rotated and with it the 20 cam sleeve 79. Formed on the periphery of the cam sleeve 79 are cams 99, Fig. 3, one such cam for each friction bar 81, and said cams are so arranged on their sleeve that they actuate said bars outwardly when 25 said sleeve is rotated to the left, and permit said bars to move inwardly when said sleeve is rotated in the opposite direction. The depth of the bars 81 is sufficient to enable them to be forced hard against the blanks 30 94, when said bars are actuated outwardly by the cams 99, and firmly to engage said blanks on the inside and hold them securely in place, at the same time exactly aligning the bars and disposing the same concentrically with the sleeve 79 and its shaft 70. The separators 80 are clear of the cams 99.

Each clamp 96 is an angular member 40 adapted to bear with the bottom edge of its vertical part on the uppermost blank 94, and with its horizontal part on the flange of the head 82, said horizontal part being slotted at 100 to accommodate one of the rods 83 below the upper end of the same. After the blanks 94 have been stacked to the required height, 45 or until approximately level with the tops of the separators 80, the clamps 96 are slipped into place beneath the nuts 84 on the rods 83, with the depending parts of said clamps bearing on the top of the uppermost blank, 50 and said nuts are screwed down tightly onto said clamps, thus forcing the latter hard against the blanks. Inasmuch as the rods 83 are screwed into the base 77, when the nuts 84 are screwed down tightly, all of the members 55 through which said rods pass are securely tied together. The binding force now exerted by the clamps 96 on the blanks 94, added to the frictional engagement existing between the bars 81 and said blanks, 60 causes the latter to be so securely and rigidly held in place on their supporting members that any movement of any blank independent of the holder is rendered impossible.

65 The flange of the head 82 may be cut

away, as shown at 101, to leave oppositely-disposed raised rims 102, Figs. 1, 3, and 6, upon which the inner ends of the clamps 96 bear. This construction insures the desired forcible contact of the clamps 96 with the 70 stack of blanks 94 when the nuts 84 are tightened.

After the blanks 94 have been cut and formed into gears, they are released so that they can be removed from their holder, by 75 loosening the nuts 84 and removing the clamps 96, and revolving the worm 89 in the direction to rotate the worm-wheel 86 to the right. The rotation of the worm-wheel 86 to the right, and the consequent 80 rotation in the same direction of the cam-sleeve 79, removes the pressure from the inner edges of the bars 81 and loosens said bars sufficiently to enable the completed gears to be lifted off of the holder. 85

The arms 90, which form guides for the friction bars 81, fall short of the blanks 94 when the latter are concentrically disposed, while the throw that may be imparted to 90 said bars by the cams 99 is sufficient to project said bars beyond the inner circumference of said blanks.

After the blanks 94 have been placed in position on their holder and clamped thereon and thereto, it is necessary that the shaft 95 70 of such holder be supplied at the upper end with a bearing support, wherefore a horizontal, vertically-movable yoke 103 and a horizontal disk 104 are provided. This disk 104 has an upwardly-extending sleeve 105, and both are bored to receive and fit over or around the upper terminal of the shaft 70. The sleeve 105 is screw-threaded at the top to receive a nut 106. The disk 104 when in operative position rests on the 100 head 82. The central portion of the hub of the yoke 103 is bored to receive the sleeve 105, and is embraced between the nut 106 above and a ball-bearing 107 below, which latter is interposed between the disk 104 and 110 said hub. The disk 104 is, therefore, free to rotate beneath the hub of the yoke 103 and on and with the shaft 70.

The shafts 70 are loosely journaled and thus able to rotate, and the parts and members mounted directly on said shafts are free thereon so that independent movement between them and the shafts is possible, but it is obvious that said shafts might be secured against rotation in their bearings, or said parts and members might be secured to said shafts, since the required results in any case would be obtained.

The head 82 has two oppositely-disposed 125 lugs 108, from which rise two posts or studs 109. The protruding portions of the studs 109 are tapered in part and end in screw-threaded terminals at the top. Tapered openings, which appear at 110—110 in Fig. 2, are provided in the disk 104 to receive the 130

protruding portions of the studs 109. Nuts 111, Figs. 4 and 5, are screwed onto the studs 109 above the disk 104. It is now clear that rotary motion imparted to the disk 104 must be communicated to the head 82 and rigidly attached parts and members, including the blanks 94.

Referring more particularly to Figs. 3, 4, and 5, it will be seen that forwardly- and rearwardly-extending wings 112 are provided on oblique webs (one of which is the web 26) at the outer ends of the uprights 3, and that these wings, together with gibs 113—113 that are bolted to the faces of said wings, afford vertical ways or guides for the inner terminals of the arms of the yoke 103, such terminals being indicated at 114—114 in Fig. 3, and there appearing also in this view vertical, V-shaped guides 115—115 that fit and slide in corresponding grooves in said wings, such guides being on the inner sides of said terminals.

The yoke 103 is counterweighted. Two cables 116 are attached at their lower terminals to the arms of the yoke, and counterweights 117 are attached to the other terminals of said cables, the latter passing over sheaves 118 that are loosely mounted on horizontal studs 119—119 supported at the proper angles by bearings 120—120 which project from the outer faces of the uprights 3 near the top and adjacent to the outer ends of said uprights. The counterweights 117 enable the yoke 103 to be moved up and down with the application of comparatively little power.

On the inner face of that portion of the front yoke arm that slides between the front wing 112 and the front gib 113 a vertical rack 121 is provided, and a short shaft 122 is journaled in said wing and protrudes from the front edge thereof to receive a crank 123—see Fig. 3. A pinion 124 is secured to the shaft 122, and said pinion intermeshes with the rack 121. The front wing 112 is recessed to receive the pinion 124. The crank 123 is secured to the aforesaid protruding terminal of the shaft 122. When the crank 123 is turned in one direction the yoke 103 is elevated, through the medium of the shaft 122, pinion 124, and rack 121, and when said crank is turned in the opposite direction said yoke is lowered, through the same medium as before.

In order to lock the yoke 103 at any desired elevation, or secure the same against accidental descent, a lock-screw 125 is tapped into the outer face of the front gib 113 and adapted to bear with its inner terminal against the corresponding face of the adjacent yoke terminal 114. This lock-screw is provided with the usual handle. When the lock-screw 125 is turned inwardly to bear forcibly against the adjacent terminal 114, it prevents the yoke from mov-

ing downwardly, but upon loosening said screw the yoke may be freely moved in either direction.

The yoke 103 is let down onto the holder beneath, by means of the pinion 112 and rack 121, over the shaft 70 and onto the head 82 of said holder, said shaft being received in the disk 104 and its sleeve 105. The sleeve 105 is actually a hub of the disk 104 for either shaft 70. At this time it may be necessary partially to rotate the disk 104 so as to bring the openings 110 in said disk into line with the studs 109 below, in order that, as the yoke descends, said studs shall enter said openings and permit said disk to come to rest on top of the head 82. The nuts 111 are then screwed onto the studs 109 above the disk 104. After the yoke has been lowered into operative position, it is secured by means of the lock-screw 125.

After the blanks 94 have been broached and converted into gears, the nuts 111 are taken off, the lock-screw 125 is loosened, and the yoke 103 with the disk 104 is raised clear of the holder, into a position such as that indicated by dotted lines in Fig. 3. The turn-table 65 is then operated to move the aforesaid holder from beneath the yoke, and the gears are removed from the holder.

Although the yoke is a part of the work holder, it is herein treated as a distinct or independent member, inasmuch as the office of the same is to center the upper terminal of the work-holder shaft, being itself removable from and replaceable on said holder.

The yoke 103 supplements the lock-pin 50 in preventing the turn-table 65 from rotating.

During the operation of the machine the work holder is intermittently rotated to index the work.

While the blanks on the inner work holder are being cut, a stack of blanks is placed on the outer work holder, and secured by means of the cam sleeve 79 and the clamps 96 and nuts 84 of said outer holder.

At the end of the gear-cutting operation performed on the first stack of blanks, the lever 24 is operated to displace the offset 49 from beneath the head 75. Next the yoke 103 is elevated by means of the crank 123, after first loosening a lock screw 125. Then the treadle 51 is operated to withdraw the lock pin 50 from engagement with the turn-table 65, and to raise said turn-table, when the latter is given a half revolution on its shaft 66 to remove the newly-formed gears on the inner work holder from the cutting field, and to carry into such field the new set or stack of blanks on the outer work holder. The turn-table is now permitted to descend onto the base 1, and the yoke 103 is actuated downwardly onto the inner work holder and connected therewith through the medium of the disk 104, studs 130

109, and nuts 111. Finally the nuts 84 and friction bars 81 are loosened and the clamps 96 removed from the work holder which at this time is the outermost holder, and the 5 gears are taken from said holder.

The inner circumference of the hollow blanks 94 is less than that of the supporting ring or flange 95, otherwise the friction bars 81 would encounter said flange and fail 10 to forcibly to engage said blanks. The required radial movement in the bars 81 is comparatively slight.

The carrier 6 is represented in its high position in Fig. 5, and in its low position 15 in Figs. 4 and 6, but this difference in positions is immaterial so far as the present invention is concerned.

What we claim as our invention, and desire to secure by Letters Patent, is—

20 1. In a work table, a support, a turn-table above said support, means adapted to lock said turn-table to said support, work holders mounted on said turn-table, said work holders consisting in part of shafts, 25 and a removable yoke adapted to be engaged with one of said shafts.

2. In a work table, a support, a turn-table above said support, a pin adapted to lock said turn-table to said support, work holders 30 mounted on said turn-table, said work holders consisting in part of shafts, and removable supporting means for the top of one of said shafts.

3. In a work table, a support, a turn-table 35 above said support, a pin adapted to lock said turn-table to said support, work holders mounted on said turn-table, said work holders consisting in part of shafts, and a removable yoke adapted to be engaged with 40 one of said shafts.

4. The combination, in a work table, with 45 a support provided with a bearing and a hollow lug, a shaft in said bearing, a turn-table mounted on said shaft and normally resting on said support, said shaft having a shouldered engagement with said turn-table, work holders mounted on said turn-table, and a lock pin in said lug and normally in engagement with said turn-table, 50 of a treadle, a pivotally-mounted lever pivotally connected with said treadle, connecting means between said pin and said lever, and a second pivotally-mounted lever pivotally connected with said treadle, said second lever having a part that forms a stirrup for said shaft, the construction and arrangement of parts being such that, when the free terminal of said treadle is depressed, said first lever withdraws said pin from locking engagement with said turn-table, and said second lever raises said shaft and elevates said turn-table with said work holders from said support, whereby said turn-table is free to be rotated.

5. The combination, in a work table, with

a support provided with a bearing and a hollow lug, a shaft journaled in said bearing, a turn-table mounted on said shaft and normally resting on said support, said shaft having a shouldered connection with 70 said turn-table, work holders, consisting in part of shafts, mounted on said turn-table, and a lock pin in said lug, said pin being adapted to engage the axial center of either of said work-holder shafts, of a treadle, a 75 pivotally-mounted lever pivotally connected with said treadle, connecting means between said pin and said lever, and a second pivotally-mounted lever pivotally connected with said treadle, said second lever having 80 a part that forms a stirrup for said shaft, the construction and arrangement of parts being such that, when the free terminal of said treadle is depressed, said first lever withdraws said pin from locking engagement with said turn-table, and said second lever raises said shaft and elevates said turn-table with said work holders from said support, whereby said turn-table is free to be rotated.

6. The combination, in a work table, with 85 a support provided with a bearing and a hollow lug, a shaft journaled in said bearing, a turn-table mounted on said shaft and normally resting on said support, said shaft having a shouldered engagement with said turn-table, work holders mounted on said turn-table, and a spring-pressed lock pin in 90 said lug, said pin being adapted to engage said turn-table, and provided with a headed spindle, of a treadle, a pivotally-mounted lever pivotally connected with said treadle, and having a part adapted to engage said headed spindle, and a second pivotally-mounted lever pivotally connected with said 95 treadle, said second lever having a member that forms a stirrup beneath said shaft, the construction and arrangement of parts being such that, when the free end of said treadle is depressed, said first lever acts to withdraw 100 said lock pin from engagement with said turn-table, and then said second lever acts to raise said shaft and elevate said turn-table from said support, so that the turn-table with its work-holders can be rotated.

7. The combination, in a work table, with 110 a support, a turn-table mounted on and adapted to be rotated about said support, work holders mounted on said turn-table, and means to lock said turn-table with either 115 of said work holders in operative position, of removable supporting means for the top of the work holder which is in operative position.

8. The combination, in a work table, with 120 a support, a turn-table mounted on and adapted to be rotated above said support, and work holders mounted on said turn-table, said turn-table being adapted to locate either of 125 said work holders in operative position, of 130

upright supporting means, a yoke having its arms slidably connected with said supporting means, and adapted to engage the top of the work holder which is in operative position, and a rack and pinion with which one of said yoke arms and said upright supporting member are provided, whereby said yoke is raised out of and is lowered into engaging position, when said pinion is rotated.

9. In a work table, a work holder comprising a shaft, a base mounted on said shaft, a cam sleeve mounted on said shaft above said base, a head mounted on said shaft above said sleeve, a plate, adapted to support the work, mounted on said sleeve above said base, separators mounted on said plate around said sleeve, friction bars slidably arranged on said plate between said separators, and adapted to be forced outwardly by said cam sleeve, means to bind together said base, head, and separators, and means to rotate said cam sleeve.

10. In a work table, a work holder comprising a shaft, a base mounted on said shaft, a cam sleeve mounted on said shaft above said base, and provided with an actuating member, a suitably mounted actuating member for said first-named actuating member, a head mounted on said shaft above said sleeve, a plate, adapted to support the work, mounted on said sleeve above said base, separators mounted on said plate around said sleeve, friction bars slidably arranged on said plate between said separators, and adapted to be forced outwardly by said cam sleeve, and means to bind together said base, head, and separators.

11. In a work table, a work holder comprising a shaft, a base mounted on said shaft, a cam sleeve mounted on said shaft above said base, a head mounted on said shaft above said sleeve, a plate, adapted to support the work, separators mounted on said plate around said sleeve, means to retain said separators in spaced relationship, friction bars slidably arranged on said plate between said separators, and adapted to be forced outwardly by said cam sleeve, and means to rotate said cam sleeve.

12. In a work table, a work holder comprising a shaft, a base mounted on said shaft, a cam sleeve mounted on said shaft above said base, a head mounted on said shaft above said sleeve, a plate, adapted to support the work, mounted on said sleeve above said base, separators mounted on said plate around said sleeve, friction bars slidably arranged on said plate between said separators, and adapted to be forced outwardly by said cam sleeve, means to bind together said base, head, and separators, such means including means for retaining said separators in spaced relationship, and means to rotate said cam sleeve.

13. In a work table, a work holder comprising a shaft, a base mounted on said shaft, a cam sleeve mounted on said shaft above said base, a plate, adapted to support a stack of hollow blanks, mounted on said sleeve above said base, separators mounted on said plate around said sleeve, friction bars slidably arranged on said plate between said separators, and adapted to be forced outwardly by said cam sleeve, means to bind together said base, head, and separators, such means including clamping means for the top of the stack of blanks, and means to rotate said cam sleeve.

14. In a work table, a work holder comprising a shaft, a base mounted on said shaft, a cam sleeve mounted on said shaft above said base, a head mounted on said shaft above said sleeve, a plate, adapted to support a stack of hollow blanks, mounted on said sleeve above said base, separators mounted on said plate around said sleeve, friction bars slidably arranged on said plate between said separators, and adapted to be forced outwardly by the cam sleeve, means to bind together said base, separators, and head, such means including means to retain said separators in spaced relationship, and also clamping means for the top of the stack of blanks, and means to rotate said cam sleeve.

15. In a work table, a work holder comprising a vertical shaft, a cam sleeve mounted on said shaft, means to actuate said sleeve on said shaft, a plurality of friction bars engaging at their inner edges said sleeve, a plurality of separators for said bars, and means to retain said separators in place.

16. In a work table, a work holder comprising a vertical shaft, a cam sleeve mounted on said shaft, and provided with a serrated member, a serrated member intermeshing with said first-named serrated member, and adapted to be operated by means of a crank to rotate said sleeve on said shaft, a plurality of friction bars in engagement at their inner ends with said sleeve, a plurality of separators for said bars, and means to secure said separators in place.

17. In a work table, a work holder comprising a base, flanged members mounted on said base, a head mounted on said flanged members, rods passing through the flanges on said members and engaging said base and head, nuts on said rods at the head ends, and clamps adapted to be interposed between the parts of said head engaged by said rods and said nuts on said rods, and to be forced onto the top of a stack of blanks on said base, by said nuts when tightened.

18. The combination, in a work table, with a turntable, work holders mounted on said turn-table, a lock-pin for said turn-table,

and means to withdraw said pin from locking position, of a rock-shaft having a locking part for said pin, a pivotally-mounted lever, pivotal connections between said lever and said rock-shaft, whereby the latter is operated to withdraw said part from locking position relative to said pin, and to restore such part to such position, and locking means for said lever.

10 19. The combination, in a work table, with a turn-table, work holders revolvably mounted on said turn-table, said holders consisting in part of shafts and heads, of a movable yoke carrying a member adapted to fit over either of said shafts, and means to attach said member to the head below.

20 20. The combination, in a work table, with a turn-table, and revoluble work holders mounted on said turn-table, said holders consisting in part of shafts and heads provided with studs, of a yoke carrying a member adapted to fit over either of said shafts, said member being perforated to receive the studs in the head below.

25 21. In a work table, a work holder comprising a shaft, a base mounted on said shaft, a cam sleeve mounted on said shaft above said base, a member, adapted to support a stack of gear blanks, mounted on said sleeve above said base, separators mounted on said member around said sleeve, friction bars slidingly arranged on said plate between said separators, and adapted to be forced outwardly by the cam sleeve, means to bind together said base, separators, and head, and means to rotate said cam sleeve.

30 22. In a work table, a work holder comprising a shaft, a base mounted on said shaft, a cam sleeve mounted on said shaft above said base, a member, adapted to support a stack of gear blanks, mounted on said sleeve above said base, separators mounted on said member around said sleeve, friction bars slidingly arranged on said plate between said separators, and adapted to be forced outwardly by the cam sleeve, means to bind together said base, separators, and head, a worm-wheel secured to said cam sleeve, and a worm for said worm-wheel.

35 23. In a work table, a work holder comprising a shaft, a base mounted on said shaft, a cam sleeve mounted on said shaft above said base, a member, adapted to support a stack of gear blanks, mounted on said sleeve above said base, separators mounted on said member around said sleeve, friction bars slidingly arranged on said plate between said separators, and adapted to be forced outwardly by the cam sleeve, means to bind together said base, separators, and head, a worm-wheel secured to said cam sleeve within said base, a shaft journaled in said base, and a worm secured to said

last-named shaft and intermeshing with said worm-wheel.

65

24. The combination, in a work table, with a support, a turn-table mounted on and adapted to be rotated above said support, and revoluble work holders mounted on said turn-table, said work holders consisting in part of shafts, of a yoke adapted to fit over the shaft of the work holder which is in operative position, supporting means for said yoke, means to attach said yoke to and detach it from said last-named work holder, and means to actuate said yoke out of and into engagement with said last-named work holder.

70

75

25. The combination, in a work table, with a support, a turn-table mounted on and adapted to be rotated above said support, and revoluble work holders mounted on said turn-table, said work holders consisting in part of shafts, of a yoke adapted to engage the shaft of the work holder which is in operative position, and to be connected with and disconnected from said holder, supporting and guiding means for the arms of said yoke, one of said arms being provided with a rack, a shaft journaled in said supporting means, a pinion secured to said shaft and intermeshing with said rack, and a crank also secured to said shaft.

80

85

90

26. The combination, in a work table, with a work holder consisting in part of a shaft, and having a head below the upper end of said shaft, a yoke carrying a member which is receivable on said head, interlocking means between said head and member, and means to raise said yoke and member from said head and shaft, and to lower said yoke and member onto said shaft and head, the upper terminal of the shaft being receivable in the yoke.

95

27. The combination, in a work table, of a work holder consisting in part of a shaft, and having a head, the latter being below the top of said shaft, a yoke, a disk having a sleeve that extends into said yoke and is revoluble therein, interlocking means between said head and disk, and means to raise and lower said yoke.

100

105

28. The combination, in a work table, with a work holder consisting in part of a shaft, and having a head, the latter being below the top of said shaft, and studs set in said head, of a yoke, a disk having a sleeve which extends into said yoke, said disk and sleeve being rotatable, and said disk having perforations to receive said studs, and means to raise and lower said yoke with said disk.
